G. P. WIGGINTON,
TEMPORARY BINDER,
APPLICATION FILED APR. 19, 1917.

1,258,383.

Patented Mar. 5, 1918.

UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

TEMPORARY BINDER.

1,258,383.

Specification of Letters Patent.

Patented Mar. 5, 1918.

Continuation of application Serial No. 77,496, filed February 10, 1916. This application filed April 19, 1917. Serial No. 163,204.

To all whom it may concern:

Be it known that I, GEORGE P. WIGGINTON, a citizen of the United States, residing at Kalamazoo, county of Kalamazoo, State 5 of Michigan, have invented certain new and useful Improvements in Temporary Binders, of which the following is a specification.

This invention relates to improvements in temporary binders.

10 The main objects of this invention are:

First to provide in a temporary binder or loose sheet holder an improved adjusting mechanism.

15 Second, to provide an improved temporary binder or loose sheet holder which is capable of rapid manipulation to permit the insertion or removal of the sheets and one which is adjusted very securely.

20 Further objects, and objects relating to structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing forming a part of this specification, in which:

30 Figure I is a detail inside plan view of a binder embodying the features of my invention with the covers extended.

Fig. II is an enlarged inverted detail of the adjusting mechanism shown in Fig. I.

35 Fig. III is an enlarged detail section on a line corresponding to line 3—3 of Fig. II.

Fig. IV is a view similar to Fig. II but showing a modified form of the clutch release.

40 In the drawing similar reference characters refer to similar parts throughout the several views, and the sectional views are taken looking in the direction of the little arrows at the ends of the section lines.

45 Referring to the drawing, the covers 1 and 2 are preferably provided with clamping bars 3 substantially as shown in my Patent No. 1,022,452, April 9, 1912. Binding members 4, preferably in the form of flexible

50 strips, extend between the covers being connected to one cover at 5 and to the other cover through my improved adjusting mechanism. The cover 2 is provided with a recess 6 in which the adjusting mechanism

is disposed. The binding strips are connected to a cross bar 7 to which the bar-like adjusting member 8 is connected at 9. The bar 8 slides in the guides 10 of the support 11 which is mounted within the recess 6 of the cover. The bar 8 is held in its adjusted position by means of the clutch roller 12 which is arranged in a support comprising an inclined way 13 disposed at an angle to the bar 8 so that when the roller travels toward the inner end of the cover it is brought into clutching engagement with the bar. A spring 14 urges the roller toward its clutching position. The roller is disengaged from its clutch position by the lever 15, which is pivoted at 16 and projects into the housing or roller support so that when the lever is actuated it releases the clutch. The lever projects at the edge of the support 11 so as to be conveniently grasped. A spring 17 is mounted on the pin 18 to return the lever 15 to its inoperative position. The bar 8 is toothed on one side to coact with the pawl 19 of the adjusting lever 20. The pawl is urged to its engaging position and the lever returned to its initial position by the spring 21 mounted on the pin 22. A stop 23 is positioned so as to engage the pawl when the lever is in its initial position, lifting the pawl from engagement with the bar.

In the modification shown in Fig. IV the clutch roller 12 is released by the lever 24 which is pivoted at 25. The lever 24 has a finger piece 26 which projects inwardly from the inner side of the support 11 so that it may be released by pushing thereon in a direction toward the outer edge of the cover. A spring 27 secured to a pin 28 tends to return the lever 24 to its normal position which is determined by a stop pin 29. With the parts thus arranged I secure a structure 80 which is simple and secure in its adjustment and capable of convenient and rapid manipulation.

This application is a continuation and division in part of my co-pending application, Serial No. 77,496, filed February 10, 1916, the embodiment of Figs. I, II and III being shown in that application.

Having thus described my invention, what I claim as new and desire to secure by Letters Patent is:

1. In a temporary binder, the combination with the covers, of binding strips extending

between the covers, a bar to which said binding strips are connected disposed on one of the covers for sliding longitudinal movement, a friction clutch member mounted on 5 the cover to coact with said bar and so that its bar engaging movement is toward the inner end of the cover, said member being automatically released by the outward movement of the bar, a spring disposed to urge 10 the clutch member to its clutching position, and a lever for disengaging said clutch.

2. In a temporary binder, the combination with the covers and a binding strip extending between the covers, of a bar to which 15 said binding strip is connected mounted on one of the covers for longitudinal movement, a spring actuated friction clutch co-acting with said bar and arranged so that its engaging movement is toward the inner

end of the cover, and a lever for disengaging 20 said clutch.

3. In a temporary binder, the combination with the covers and a binding strip extending between the covers, of a bar to which 25 said binding strip is connected mounted on one of the covers for longitudinal movement, a spring actuated friction clutch co-acting with said bar and arranged so that its engaging movement is toward the inner 30 end of the cover, and means for disengaging said clutch.

In witness whereof, I have hereunto set my hand and seal in the presence of two witnesses.

GEORGE P. WIGGINTON. [L.S.]

Witnesses:

ELIZABETH K. OWENS,

WALTER M. ELY.
